FRANK E. SEELEY, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

INCANDESCENT-LAMP SOCKET.

No. 918,477.

Specification of Letters Patent.

Patented April 13, 1909.

Application filed April 21, 1908. Serial No. 428,398.

To all whom it may concern:

Be it known that I, FRANK E. SEELEY, a citizen of the United States of America, and residing at Bridgeport, in the county of Fairfield and State of Connecticut, have invented 5 a certain new and useful Improvement in Incandescent-Lamp Sockets, of which the following is a specification.

This invention consists in an improvement 10 in incandescent lamp sockets and particularly in key sockets, the object of my invention being to provide an insulated metal key the efficiency of which is unaffected by the heat of the lamp.

15 In the accompanying drawings illustrating my invention in one form, Figure 1 is a perspective view of the key spindle and its bearings; Fig. 2 is a cross section of the spindle looking toward the contact piece; Fig. 3 is a 20 cross section of the latter; and Fig. 4 is a section of one of the insulating bushings for the bearing of the spindle.

In the sockets in general use in which a metal key is used it is customary to insulate 25 the latter from the spindle carrying the contact piece by mounting a bushing with an insulating lining on the end of the spindle and securing the key to the bushing. The heat of the lamp however is frequently sufficient to soften the insulating lining of the 30 bushing to such an extent that its purchase upon the spindle is so weakened that when the key is turned the bushing merely swivels upon the spindle without actuating it. To 35 obviate this disadvantage I propose to thread the key 6 directly upon the spindle 7, and insulate the latter by suitable means from the electrically live parts of the socket with which it is in contact in the construction now 40 in general use. To this end I insert insulating bushings 8 in the bearings for the spindle in the standards 9 and 9^a of the plate 10, to which one of the leading in wires is attached through the binding screw 11. The rotary 45 contact piece which is carried by the spindle is insulated therefrom in any suitable manner—as for instance by forcing a band 12 of

conducting material over a shell 13, bearing an envelop 14 of insulating material. The inner face of the shell which is preferably of metal 50 presents a rigid surface for the wings 15 on the spindle to bear against and also affords a satisfactory bearing for the contact piece on the spindle which passes through the hole 16, while the envelop 14 thoroughly insulates the band and shell from each other. The presence of the insulating material on the outer face of the shell serves also to prevent accidental contact between the standard 9^a and the contact piece. 55

60 The particular construction which I have disclosed may be readily varied without departing from the scope of my invention as indicated in the following claims and I do not limit myself to the details shown. 65

I claim as my invention:

1. An electrical device of the character described, having a rotary spindle and a contact piece carried thereby, comprising an external conducting band, a shell within the 70 same and an interposed insulating envelop.

2. An electrical device of the character described, having a rotary spindle and a contact piece carried thereby, comprising an external conducting band, a shell within the 75 same and an interposed insulating envelop completely covering the outer surface of the latter.

3. An electrical device of the character described having a rotary spindle and a contact piece carried thereby, comprising an external conducting band, a shell within the 80 same and an interposed insulating envelop, said shell being perforated to permit the passage of the spindle therethrough and forming 85 a bearing therefor, substantially as described.

In testimony whereof I have signed my name to this specification, in the presence of two subscribing witnesses.

FRANK E. SEELEY.
